HYDRAULIC TRANSMISSION

Fritz Kugel, Heidenheim, Brenz, Germany, assignor to American Voith Contact Co. Inc., New York, N. Y., a corporation of New York

Application April 25, 1939, Serial No. 269,873
In Germany April 26, 1938

10 Claims. (Cl. 60—54)

This invention relates to hydraulic machinery, and in particular, to hydraulic power transmitters, such as hydraulic couplings or torque converters.

One object of this invention is to provide a hydraulic torque converter having either its primary or secondary rotor or both of them constructed as a plurality of blade assemblies connected to a common shaft, but spaced apart from each other so that the different blade assemblies are subjected by the working fluid to different forces, the vane configuration or profile being varied between the assemblies to provide the most suitable form for the operating conditions in the channels between the blades in the particular blade assembly.

Another object is to provide a hydraulic power transmitter, wherein the blades of at least one of the rotors are divided up into at least two assemblies, spaced apart from each other and having blade constructions or cross sections which differ considerably between the two or more blade assemblies so that the blade cross section for each assembly can be made most favorable for the particular fluid conditions which that blade assembly encounters.

Another object is to provide a hydraulic power transmitter, such as a torque converter, with primary and secondary rotors, one of these rotors having a plurality of blade assemblies, at least one of these blade assemblies in the multistage rotor being constructed and arranged as a pump rotor, whereas at least one of the other blade assemblies connected to the same rotor is constructed and arranged as a turbine rotor.

Another object of this invention is to provide a hydraulic power transmitter, such as a torque converter, with primary and secondary rotors, each of these rotors having a plurality of blade assemblies, at least one blade assembly of each of the multistage rotors being constructed and arranged as a pump rotor, and at least one blade assembly connected to the same rotor being constructed and arranged as a turbine rotor.

These and other objects and advantages of the invention will appear more clearly from the following specification in connection with the accompanying drawings, in which:

Figure 1 is a cross section through a blade of a blade assembly pertaining to a torque converter according to the invention and graphically illustrates the velocities and the way of movement of a liquid particle.

Figure 2 shows, on an enlarged scale, the velocity triangles of Figure 1.

Figure 3 diagrammatically illustrates a longitudinal section through a torque converter according to a first embodiment of the invention.

Figures 4, 5, 6 and 7 respectively show the entrance and exit velocities for the various blade assemblies of Figure 3.

Figure 8 is a diagrammatic illustration of a second embodiment of the invention.

Figures 9, 10, 11 and 12 respectively show the entrance and exit velocities of the various blade assemblies of Figure 8.

Figure 13 is a third embodiment of the invention, and

Figures 14, 15, 16, 17 and 18 illustrate the various velocities of the blade assemblies pertaining to Figure 13.

General arrangement

In general, the hydraulic power transmitter of the present invention consists of a casing containing primary and secondary rotors, one of the 15 rotors having its blades distributed among a plurality of blade assemblies. These blade assemblies are separated or spaced from each other along the orbital path followed by the working fluid. As the velocity and pressure conditions of 20 the working fluid vary in the path followed thereby, it is thus possible to adapt for each blade assembly a blade configuration, cross section or profile which is most efficiently formed and therefore most favorable in its operation for 25 the particular condition of the working fluid at that point in the circuit. In particular, the embodiment chosen for purposes of illustration shows a torque converter with a primary rotor having a single stage, namely, a single blade assembly having a pump action. In contrast, however, the secondary rotor consists of a plurality of blade assemblies having a turbine action.

Hitherto, in order to obtain a good working 30 efficiency in hydraulic torque converters, it has been found that as great as possible an acceleration of the relative flow of the working fluid should occur within the blade channels during operation because a retardation of the flow inside a blade channel causes a transformation of kinetic 35 energy into potential energy, which is invariably accompanied by great losses in efficiency. To obtain the said acceleration of the relative flow of the working fluid, the blades have to be given a certain definite shape. Furthermore, provision 40 must be made for securing a satisfactory admission of the working fluid to the inlet edges of the blade assemblies under widely varying operating conditions, such as are usually met with in 45 torque converters; to meet this last mentioned requirement, the inlet edges of the vanes are given a substantial thickness and are shaped on the lines of the Göttingen wing section, whereas 50 the exit portions of the blades must be as sharply tapered as possible.

This construction, however, produces greatly diverging blade channels, particularly if the entrance and exit angles at which the fluid enters and leaves the blade assemblies differ only slightly 55 from each other. These angles are dependent,

aside from other factors, upon the pressure head to be converted in the particular blade assembly. The greater this pressure head the more the entrance and exit angles must differ from one another, and hence, the more closely will the blade approach the ideal theoretical blade profile.

With torque converters, particularly when used in connection with vehicles, it is desirable when starting the vehicle to allot only a small total pressure head to the rotors in order to obtain a powerful torque conversion. However, when using torque converters with multi-stage rotors, this way of operation has the disadvantage that only a small pressure head can be utilized in each stage according to the particular operating conditions, since the total pressure head upon the individual stages is divided up into positive portions so that the sum of the pressure heads to be employed in the individual stages of the particular rotor is equal to the desired total pressure head employed.

Therefore, with multi-stage torque converters, various conditions prevail which make the construction of blades of the most favorable form rather difficult. On one hand, the greater number of blade assemblies leaves less space for the adequate and proper construction and shape of the blade surfaces, and, on the other hand, the pressure head to be converted in each individual stage is in general lower than is desirable. As mentioned above, it is much easier to obtain the best possible blade form when a large pressure head is to be employed rather than when only a small pressure head is obtainable, keeping in mind that it is desired to speed up the flow of fluid within the blade channels, or at least to prevent a decrease in the velocity of the fluid which would reduce the efficiency of the torque converter.

The above-mentioned drawbacks have been overcome according to the present invention by providing a fluid power transmitter with at least one multistage rotor, wherein one or more stages are constructed as pressure head-generating rotors or pump rotors (or impeller vane rings), whereas one or more stages are constructed as pressure head-consuming rotors, such as turbine rotors. By this construction a great freedom of choice is provided in selecting the value of the pressure which is most efficiently suited to the particular blade form at that point in the circuit.

With torque converters having single stage rotors, in fixing the particular pressure head to be utilized in the circuit as well as the magnitudes of the other operating factors the blade form of the individual rotor is more or less positively determined. In previous torque converters with multi-stage blade assemblies, the distribution of the different pressure heads among the individual assemblies is brought about in such a manner that all blade assemblies of a given rotor operate in the same manner. In other words, all of the blade assemblies of the primary side of the torque converter work always as pumps, whereas all of the blade assemblies of the secondary side work always as turbines.

In contrast to this prior development in a torque converter, according to the present invention the individual blade assemblies of a given rotor do not all work in the same manner but in different ways. In other words, the primary rotor, as regards its individual stages, does not consist solely of pressure head-generating blade as-

semblies, that is to say, pump blade assemblies, but the primary rotor also contains one or more pressure head-consuming blade assemblies, namely, blade assemblies operating in the manner of turbines.

The pressure head H to be converted by one blade assembly can be expressed by the following equation:

$$10 \quad H = \frac{u_2 c_{u2} - u_1 c_{u1}}{g}$$

where

H =pressure head.

15 u_1 =circumferential speed at the entrance of vanes (see Figure 1).

u_2 =circumferential speed at the exit of vanes.

c_{u1} =projection of the absolute entrance speed c_1 (see Figure 1) upon the circumferential speed u_1 (see Figure 2).

20 c_{u2} =projection of the absolute exit speed c_2 upon the circumferential speed u_2 .

g =acceleration due to gravity.

According to the invention, at least two blade assemblies ought consequently to be fixed rigidly on one or on both shafts of a fluid transmission of which one blade assembly converts a positive H and the other a negative H . The algebraic sum of the pressure heads of all those blade assemblies connected with the primary shaft has, of course, to be positive to correspond to pumping action and the algebraic sum of the pressure heads of all the blade assemblies connected with the secondary shaft has to be negative to correspond to turbine action.

From Figures 1 and 2, it will be clear that

$$\cos \beta_1 = \frac{U_1 - Cm_1}{Cm_1}$$

40 wherein β_1 is the entrance angle of the vanes, and Cm_1 is the relative velocity at the entrance of the vanes, i. e., the velocity of a fluid particle relative to the respective vane; or

$$45 \quad Cu_1 = U_1 - Cm_1 \cos \beta_1$$

Similarly

$$\cos (180^\circ - \beta_2) = -\cos \beta_2 = \frac{Cu_2 - U_2}{Cm_2}$$

50 or

$$Cu_2 = U_2 - Cm_2 \cos \beta_2$$

Since

$$U_1 = Wr_1$$

and

$$U_2 = Wr_2$$

wherein W is the angular velocity of the wheel or rotor in radians per second; r =radius of the entrance edge of the vanes; r_2 =radius of the exit edge of the vanes, the equation

$$H = \frac{U_2 Cm_2 - U_1 Cm_1}{g}$$

may be written as follows:

$$65 \quad gH = W^2 r_2^2 - Wr_2 Cm_2 \cos \beta_2 - W^2 r_1^2 - Wr_1 Cm_1 \cos \beta_1$$

Since furthermore

$$Cm_1 = \frac{Q}{f_1}$$

and

$$Cm_2 = \frac{Q}{f_2}$$

70 75 wherein f_1 =cross sectional area of fluid passage

at the entrance of the vanes, and f_2 =cross sectional area at the exit of the vanes.

$$gH = W^2(r_2^2 - r_1^2) - Wr_2 \frac{Q}{f_2} \cos \beta_2 - Wr_1 \frac{Q}{f_1} \cos \beta_1$$

$$gH = W^2(r_2^2 - r_1^2) - WQ\left(\frac{r_2}{f_2} \cos \beta_2 - \frac{r_1}{f_1} \cos \beta_1\right)$$

$$\frac{gH}{WQ} = \frac{W}{Q} (r_2^2 - r_1^2) - \left(\frac{r_2}{f_2} \cos \beta_2 - \frac{r_1}{f_1} \cos \beta_1 \right)$$

It is evident from this equation that the sign of the pressure head H is dependent upon various values. After the entrance and exit radii r_1 and r_2 of the vanes have been determined in accordance with the particular requirements of the respective case, the pressure is substantially dependent on the entrance and exit angles β_1 and β_2 . With the aid of the above equations, the designer will be in a position to provide the primary or the secondary shaft, or both shafts of a fluid transmission with pump blade assemblies as well as with turbine assemblies according to the invention.

Construction

Referring now to the structural arrangements in detail, Figure 3 shows one embodiment of the invention as consisting of a torque converter having a primary shaft W_1 and a secondary shaft W_2 . Connected to the primary shaft W_1 is a primary rotor P having a singleblade assembly P_1 with a primary core ring P_2 . Connected to the secondary shaft W_2 is a secondary rotor S provided with two stages or blade assemblies S_1 and S_2 , spaced apart from each other and mounted upon the secondary core ring S_3 . The torque converter is also provided with a casing C , consisting of casing halves C_1 and C_2 , rotatably mounted by means of anti-friction bearings B_1 and B_2 upon the primary and secondary shafts W_1 and W_2 . The casing C is provided at its periphery with a brake surface D , adapted to be engaged by a brake E , whereby the rotation of the casing C may be retarded. Connected to the casing half C_2 is a guide blade assembly L , which may be made to occupy a stationary position by the application of the brake E to the brake surface D .

The form or profile of the blades in Figure 3 as well as the velocity triangles therefor are illustrated in Figures 4, 5, 6 and 7. More specifically, the blade assembly P_1 , or 1-2 in Figure 3, which is a pump blade assembly, has the blade profile shown in Figure 4 between the lines 1 and 2. In addition thereto, Figure 4 shows the vector or velocity diagrams for the fluid particles at the entrance and exit of the vanes shown in Figure 4. Thus, U_1 and U_2 respectively illustrate the circumferential speed or velocities at the entrance and exit of these vanes, while C_{m1} and C_{m2} represent the relative velocities and C_1 and C_2 represent the absolute velocities at the entrance and exit of these vanes.

Similarly, the blade assembly S₁, or 3-4 in Figure 3, which is a turbine blade assembly, has the blade profile shown in Figure 5 between the lines 3 and 4. Figure 5 also shows the vector or velocity diagrams pertaining to these vanes.

The guide blade assembly L, or 5-6 of Figure 3, which, as mentioned above, may be held stationary by applying the brake E to the brake surface D, has its profile illustrated in Figure 6 between the lines 5 and 6. With the assumption that the guide blade assembly is held stationary,

only absolute velocities occur at the entrance and exit of the guide blade assembly, and these velocities are designated in Figure 6 as C_5 and C_8 respectively.

- 5 The blade assembly S_2 , or 7-8 of Figure 3, which is a pump blade assembly, has its profile illustrated between the lines 7 and 8 in Figure 7. Figure 7 also illustrates the velocity diagrams pertaining to the blade assembly 7-8.

10 From the above it will be clear that by providing one and the same rotor with a positive pressure head converting blade assembly and with a negative pressure head converting blade assembly, the form of the blade assembly can be designed with the most favorable profile for the working conditions of the fluid as they exist at that particular point in the orbital path of the fluid within the torque converter.

15 By forming one of the stages of the secondary rotor, such as the blade assembly S_2 , as a pump blade assembly, which is, in effect, driven by the turbine blade assembly S_1 , the speed and, therefore, the force of the fluid will be additionally increased beyond that imparted by the primary or pump blade assembly P_1 .

20 With reference to the design of the blade forms of the torque converter shown in Figure 3, the blade assemblies are so selected that, if the secondary side of the converter has to operate with a total pressure of the value a , whereas for obtaining a favorable blade form, a pressure of the value b is necessary, this value b being absolutely greater than the value a , the first stage S_1 may be allotted a pressure of the value a plus b , and the second stage can be allotted the pressure of the value $-b$. By this means a favorable blade form can be achieved for both stages. In practice, however it may also be sufficient if the pressure head for the first stage S_1 is chosen only slightly higher than the desired value a for achieving a favorable blade construction as regards acceleration in the blade channels because the second stage S_2 can be located at a position in the working circuit which is favorable for the development of the vane profile; so that for this stage also a favorable vane shape (that is one providing acceleration in the vane passages) can be obtained with only a low head.

Operation

In the operation of the hydraulic power transmitter of the invention, such as the torque converter shown in Figure 3, the primary shaft W_1 is rotated by being connected to a source of power, such as an internal combustion engine, the working chamber within the casing C being then filled with working fluid, such as oil, to the desired extent. Under the influence of the rotation of the blade assembly P_1 of the primary rotor P , the oil is caused to circulate in an orbital path and successively engages the secondary blade assembly S_1 , the guide blade assembly or guide wheel L and the secondary blade assembly S_2 , before returning to a subsequent engagement with the primary blade assembly P_1 .

As previously stated, the division of one of the rotors, such as the secondary rotor S, into multiple stages enables the blades of each stage S_1 and S_2 to be given the most suitable form for the attainment of the highest efficiency in view of the condition of the working fluid in the blade channels thereof. Consequently, the retardation of the working fluid as it passes through the blade channels is effectively prevented, and acceleration is imparted thereto which prevents

the losses in efficiency occurring in previously known torque converters lacking this provision, and permitting this retardation of the working fluid. If one of the blade assemblies S_1 or S_2 is given opposite characteristics from the other, as previously explained, such as when one is caused to exert a pump action and the other a turbine action, the operating characteristics and behavior of the working fluid may be so predetermined that the blade forms or profiles in the two different stages S_1 and S_2 can be given their most suitable configurations according to the circumstances.

During the starting up period of the vehicle, the casing C may be prevented from rotating by applying the brake E . At higher speeds the brake E may be released and the casing C permitted to rotate. Thus, according to the invention, the provision of multiple stages on one or on both of the rotors and the consequent adaptation of the blade assemblies and their cross sections or profiles to the speed and force characteristics of the working fluid existing in the blade channels between the blades, can be most efficiently correlated to the end that the torque converter operates most efficiently under greatly varying conditions of operation.

Referring now to Figure 8, the structure shown therein illustrates a torque converter with two primary blade assemblies and one secondary blade assembly. The primary rotor P comprises a pump blade assembly P_1 , or 1-2, and also a turbine blade assembly P_3 , or 5-6, whereas the secondary rotor comprises the turbine blade assembly S_1 , or 3-4. The guide wheel assembly is designated L , or 7-8, and may be held stationary by any convenient means. As to the remaining elements of Figure 8, these correspond to the elements of Figure 3 carrying the same reference characters as in Figure 8.

The profiles of the blade assemblies 1-2, 3-4, 5-6, and 7-8 of Figure 8 as well as the velocity diagrams pertaining thereto are illustrated in Figures 9, 10, 11 and 12 in a manner similar to that described above in connection with Figures 3 to 7. The device of Figure 8 operates similarly as the structure of Figure 3 and will be understood without further description.

Figure 13, illustrating a further embodiment of this invention, shows a torque converter with two primary and two secondary blade assemblies. The primary rotor P comprises a pump blade assembly P_1 , or 1-2, and also a turbine blade assembly P_3 , or 5-6, whereas the secondary rotor comprises a turbine blade assembly S_1 , or 3-4, and a pump blade assembly S_2 , or 7-8. The guide wheel assembly is designated L , or 9-10, and may be held stationary by any convenient means. Otherwise, the structure of Figure 13 comprises similar to the device of Figure 8, a driving shaft W_1 , a driven shaft W_2 and ball bearings B_1 and B_2 for supporting the casing which surrounds the blade assemblies P_1 and P_3 and is connected to the shaft W_2 .

The blade assemblies 1-2, 3-4, 5-6, 7-8, and 9-10, have their profiles shown in Figures 14, 15, 16, 17 and 18 respectively. These figures also show the velocity diagrams pertaining to these profiles in a manner similar to that described in connection with Figures 3 to 7.

It is, of course, understood that the present invention is not limited to the particular structure shown in the drawings but also embraces any modifications within the scope of the appended claims.

Having thus fully described my invention, what I claim as new and desire to secure by Letters Patent, is:

- 5 1. In a fluid power transmitter, a first rotor, a second rotor, each of said rotors having rigidly connected thereto a pressure head generating blade assembly, and at least one of said rotors having also rigidly connected thereto a pressure head consuming blade assembly, and a guide blade assembly interposed between two adjacent blade assemblies for guiding the fluid therebetween.
- 10 2. In a fluid power transmitter, a primary rotor having a pumping blade assembly, a secondary rotor having a pumping blade assembly and a turbine blade assembly, and a guide blade assembly interposed between said pumping blade assembly and said turbine blade assembly of said secondary rotor.
- 15 3. In a fluid power transmitter, a primary rotor having rigidly connected thereto a turbine blade assembly and a pumping blade assembly, a guide blade assembly interposed between said pumping blade assembly and said turbine blade assembly, and a secondary rotor having a turbine blade assembly.
- 20 4. A fluid power transmitter comprising in combination a primary rotor, a secondary rotor hydraulically connected with said primary rotor, each of said rotors having rigidly connected thereto a pumping blade assembly and one of said rotors having also rigidly connected thereto a turbine blade assembly, and a guide blade assembly arranged between two blade assemblies of the same rotor for guiding the fluid therebetween.
- 25 5. In a torque converter, a rotatable casing, a brake engageable with said casing to selectively halt the rotation of said casing, a primary rotor and a secondary rotor, both rotors being arranged within and rotatable relative to said casing, each of said rotors having rigidly connected thereto a plurality of blade assemblies including a pumping blade assembly and a turbine blade assembly, and a guide blade assembly secured to said casing and arranged between two adjacent blade assemblies not pertaining to one and the same rotor.
- 30 6. A torque converter, comprising in combination a rotatable casing, a brake engageable with said casing to selectively halt rotation of said casing, a first rotor and second rotor within said casing, said first rotor having rigidly connected thereto at least one blade assembly and said second rotor having rigidly connected thereto a plurality of blade assemblies including a pressure head generating blade assembly and a pressure head consuming blade assembly, and a guide blade assembly secured to said rotatable casing and disposed between two adjacent blade assemblies.
- 35 7. In a fluid power transmitter, a primary rotor, a secondary rotor, at least one of said rotors having rigidly connected therewith at least one pressure head generating blade assembly and at least one pressure head consuming blade assembly, and a guide blade assembly, said blade assemblies being arranged so that following the direction of flow of fluid in said transmitter each blade assembly of one rotor is followed by one of the other blade assemblies not pertaining to the same rotor, while said guide blade assembly is followed by a blade assembly pertaining to one of said rotors.
- 40 8. In a fluid power transmitter, a primary rotor having rigidly connected thereto a pressure head

generating blade assembly and a pressure head consuming blade assembly, a secondary rotor having rigidly connected thereto a pressure head consuming and a pressure head generating blade assembly, and a guide blade assembly arranged between two adjacent blade assemblies, one of which pertains to one rotor, while the other pertains to the other rotor.

9. In a fluid power transmitter, a primary rotor having a pressure head generating and a pressure head consuming blade assembly, a secondary rotor having rigidly connected thereto a pressure head consuming and a pressure head generating blade assembly, said blade assemblies being ar-

5 ranged so that following the direction of flow of fluid in said transmitter each blade assembly of one of said rotors is followed by a blade assembly of another rotor, and a guide wheel blade assembly interposed between two of said blade assemblies.

10. In a fluid power transmitter, a primary rotor having a pressure head generating blade assembly, a secondary rotor having rigidly connected thereto a fluid pressure consuming and a fluid pressure generating blade assembly, and a guide wheel blade assembly interposed between two of said blade assemblies.

FRITZ KUGEL.
